UNITED STATES PATENT OFFICE.

WILLIAM A. KING, OF MEMPHIS, TENNESSEE.

DESIGN FOR AN AUTOMOBILE-FENDER.

57,661.

Specification for Design.

Patented Apr. 26, 1921.

Application filed July 9, 1920. Serial No. 395,169. Term of patent 14 years.

To all whom it may concern:

Be it known that I, WILLIAM A. KING, a citizen of the United States, residing at Memphis, in the county of Shelby and State of Tennessee, have invented a certain new, original, and ornamental Design for an Automobile-Fender, of which the following is a specification.

Figure 1 is a view of the new and ornamental fender in front elevation.

Fig. 2 a view of the fender in side elevation,

Fig. 3 a view of the fender in top plan.

The fender is of such curvature as is necessary to fit over and protect the wheel of an automobile upon which it is used, such curvature being indicated at 10. An apron 11 extends from one side of the curved portion of the fender such apron being mechanically employed for attaching to the body of the automobile. The fender itself comprises oppositely inclined side bands 12 and 13 with central band 14 sub-

stantially normally horizontal in cross section. At the end the side bands 12 and 13 are clipped at their corners, as indicated at 15 and 16, respectively, with the central band 14 terminating in a downwardly extending section 17. A bead 18 is employed about the edge of the bands 12, 13 and 14 dividing the said bands from a curtain 19 which extends under the curved front edge of the fender.

I claim—

The new original and ornamental design for an automobile fender as shown and described.

In witness whereof, I have hereunto set my hand at Indianapolis, Indiana this 30th day of June, A. D. nineteen hundred and twenty.

WILLIAM A. KING.

Witnesses:

M. L. SHULER,

C. M. LORENZ.
